5 Claims. (Cl. 424—300)

ABSTRACT OF THE DISCLOSURE

The treatment of Parkinsonism in humans with N,N-diphenyl carbamates of alkylaminoalkanols.

This application is a continuation-in-part of application Ser. No. 183,356, filed Mar. 29, 1962, now abandoned.

This invention relates to a method of treating Parkinsonism in humans and more particularly relates to the method of treatment of all types of Parkinsonism by administering to the patient certain basic carbamates or pharmaceutically acceptable salts thereof.

It is known that certain substances with an atropine-like (anticholinergic) action can be used as remedies for treating Parkinsonism. For this purpose centrally acting anticholinergic compounds are needed, which would be devoid as far as possible of peripheral anticholinergic (e.g. antispasmodic) activity.

It probably never will be possible to find a substance showing either exclusively central or exclusively peripheral actions. As a matter of fact, preparations hitherto used for the treatment of Parkinsonism also produce side effects like inhibition of salivation, mydriasis (enlargement of the pupils) etc., caused by the peripheral anticholinergic components of their activity.

R³ is ethylene. These compounds can be synthesized by analogy to the methods known in the art, e.g., according to German Patent No. 272,529.

Typical examples of compounds which may be utilized in the method of treatment of the present invention are the N,N-diphenylcarbamates of the following alkylaminoalkanols:

- 2-dimethylaminoethanol
- 2-diethylaminoethanol
- 2-methylethylaminoethanol
- 2-dipropylaminoethanol
- 2-ethylpropylaminoethanol
- 2-dibutylaminoethanol
- 2-propylbutylaminoethanol
- 15 3-diethylaminopropanol-(1)
- 2-dimethylaminopropanol-(1)
- 2-diethylaminopropanol-(1)
- 2-dimethylamino-2-methylpropanol-(1)
- 3-dimethylamino-propanol-(2)
- 20 3-diethylamino-propanol-(2)
- 5-dimethylamino-pentanol-(2)
- 5-diethylaminopentanol-(2)

In addition to the above compounds there may be used each of the following carbamates of the above listed alkylaminoalkanols:

- N-(o-chlorophenyl)-N-phenylcarbamate
- N-(3,4-dichlorophenyl)-N-phenylcarbamate
- N,N-di-(o-chlorophenyl)-N-phenylcarbamate
- 30 N-(o-methylphenyl)-N-phenylcarbamate
- N-(p-chlorophenyl)-N-phenylcarbamate
- N,N-di-p-tolylcarbamate
- N-(m-methoxyphenyl)-N-phenylcarbamate

35 A clinically useful antiparkinson substance generally inhibits tremors, produced in mice by a preliminary treatment with tremorin. The antitremor activity of our compounds has been compared on tremorin treated mice with the prior art antiparkinson drugs according to the method of Everett et al., vide Science 124, 79 (1965). Some of the results are given in the following table (Table I):

TABLE I

Drug	I LD ₅₀ , mg./kg., p.o. ¹	II Tremor-inhi- bition, ED ₅₀ ^t , mg./kg. p.o. ²	III LD ₅₀ /ED ₅₀ ^t	IV Mydriasis ED ₁₀ ^m , mg./kg. p.o. ³	V ED ₁₀ ^m /ED ₅₀ ^t
Phenyltarimid	4,1,200	17	70	10	0.6
Biperiden	4,545	9	61	10	1.1
Trihexyphenidyl	4,365	13	28	24	1.8
Orphenadrin, i.e. C ₆ H ₅ o-CH ₂ C ₆ H ₄ >CHO(CH ₂) ₂ N(CH ₃) ₂ ·HCl	310	14.5	21	35	2.4
SD-25, i.e. (C ₆ H ₅) ₂ NCOO(CH ₂) ₂ N(C ₆ H ₅) ₂ ·HCl	270	3	90	88	28

¹ Amount of substance in mg./kg. perorally administered necessary to produce 50% lethality determined by the method of Litchfield and Wilcoxon, J. Pharmacol. 96, 99 (1949).

² For inhibition of tremor in 50% of mice treated with tremorin (average dose).

³ The dose necessary for a pupil diameter increase of 10 scale units.

⁴ Values taken from Frommel and Flury, J. Suisse Med. 88, 713 (1958).

We made the discovery that there exists a group of substances with an unexpected high prevailing central anticholinergic action. This group of substances are carbamates of the general structure:

wherein R¹ and R² are the same or different groups selected from the class consisting of phenyl, lower alkyl-phenyl, lower alkoxy-phenyl and halo-phenyl, R³ is lower alkylene and R⁴ and R⁵ are the same or different lower alkyl groups. In the preferred class of compounds R¹ and R² are phenyl, R⁴ and R⁵ are methyl or ethyl and

60 It should be noted that a compound is considered to be valuable for the treatment of tremor (Parkinsonism) if its ED₅₀^t value is low. In the third column (III) of the table a high LD₅₀/ED₅₀^t figure indicates the combination of good antitremor activity with low toxicity. In the fourth column a high figure indicates low mydriasis (undesired side effect). In the fifth column a high figure is an expression for high antitremor activity combined with a low undesired side effect. Since for our compound SD-25 this value (28) is more than ten times higher than the next best compound (2.4), it is obvious that SD-25 represents surprisingly favorable effects. The comparison 65 with orphenadrin further demonstrates that in this field structural resemblance does not enable prediction of a

specific kind of biological activity. Besides SD-25, its lower homologue, containing two methyl groups instead of the two ethyls of SD-25, is a particularly effective antitremorine agent.

The compound SD-25 is known in the literature approximately since 50 years and its local anesthetic effect and other pharmacodynamic properties have been described. Sekera and Vrba (Arc. Int., Pharmacodyn, 125, 316, 1960) state that their S-25 (identical with our SD-25) possesses 0.5-1 times the anticholinergic action of the well known spasmolytic agent Trasentine. Trasentine is a mainly musculotropically acting, i.e. a papaverine-like antispasmodic; it is evaluated in general against BaCl₂-induced spasms. Its peripheral anticholinergic action (as determined on the acetylcholine produced spasm of intestines) amounts only to 1/20 of the action of atropine (cf. L. Meier, Klin. Wochenschrift 39, 1403 (1936)). Therefore the statement of Sekera and Vrba suggests that the anticholinergic activity of SD-25 on the rabbit ileum is only 1/20-1/40 of the activity of atropine. According to our own experiments of the effect of SD-25 against acetylcholine induced spasms on the isolated guinea pig ileum is even only 1/500 that of atropine.

This, in addition to our observation of the low mydriatic effect of SD-25 proves, that this substance has only a rather slight peripheral anticholinergic effect.

The central cholinergic activity of SD-25, as required for Parkinson remedies and as demonstrated on tremorine treated rats, by us in this application, never has been described before.

For obvious reasons, when isolating any of the compounds of Formula I in the form of an acid addition salt, the acid is preferably selected so as to contain an anion which is non-toxic and pharmacologically acceptable at least in usual therapeutic doses. Representative acid addition salts are hydrochlorides, hydrobromides, sulphates, phosphates, nitrates, acetates, lactates, maleates, citrates, tartrates and bitartrates, succinates, oxalates, methanesulphonates and ethanesulphonates. Other acid addition salts are likewise suitable and may be employed if desired.

Clinical trials with the hydrochloride of the N,N-diphenylcarbamate of 2-diethylaminoethanol (SD-25) have proven the good therapeutic effects of this substance concerning rigor and tremor, when administered to patients suffering from diseases of the extra pyramidal system, e.g. true Morbus Parkinson or parkinsonism of an arteriosclerotic or postencephalic origin. Furthermore it can be used for the treatment of extrapyramidal symptoms, such as trismus, the tongue-gorge syndrom, spastic rigor and tremor, produced as undesired side effects, when neuroleptics such as reserpine or phenothiazines, e.g. 10-[gamma-(N-methyl piperazino)-propyl]-phenothiazine-2-sulfonic acid dimethylamide ("thioperazine") are administered to patients (medicamental parkinsonism). SD-25 can be administered either together with the neuroleptic agent, afterwards or even before.

SD-25 is well tolerated and no deleterious effects have been observed, even when the drug was given for more than one year. The patients do not complain of dryness of the mouth or other side effects, which frequently are observed when other antiparkinson remedies are administered.

SD-25 can be given perorally and parenterally (intravenously or intramuscularly) in average doses of 15 to 50 mg., 2-4 times p.d. It is possible to inject it i.v. re-

peatedly within a time interval of 15 to 30 minutes, whereby in certain cases particularly good therapeutic results have been obtained.

For injection purposes a 1-3%, preferably 2.5% aqueous solution, containing 25 mg. of SD-25 per ml. is generally used. For peroral treatment for instance 2-4 tablets of 25 mg. SD-25 are given daily. Of course, the optimal dose is individually different and can be ascertained by the physician for singular cases.

It will be understood that the compositions used in the present invention can be brought into a unit dosage form by any suitable technique known to the man skilled in the art. A typical example of a method to prepare tablets containing the preferred 2-diethylaminoethyl-N-diphenylcarbamate will be given below:

	Grams
2-diethylaminoethyl-N-diphenylcarbamate hydrochloride	25
Milk sugar powder	50
20 Highly dispersed silicic acid (trademark "Aerosil")	10
Potato starch	85

are intimately blended and then granulated. After addition of

	Grams
25 Stearic acid powder	10
Powdered agar agar	10
Highly dispersed silicic acid ("Aerosil")	10

the so obtained mass is intimately mixed again and pressed into 1000 tablets containing each 25 mg. of the said active ingredient. Instead of the above carriers there can be used of course any other suitable carriers such as talc, mannose, corn starch, magnesium stearate, etc.

We claim:

35 1. A method of treating parkinsonism in human comprising administering to said humans afflicted with parkinsonism an effective amount of a compound selected from the group consisting of compounds having the following formula and pharmaceutically acceptable acid addition salts thereof

wherein R¹ and R² are phenyl, R³ is lower alkylene and R⁴ and R⁵ independently are lower alkyl.

2. A method according to claim 1, wherein R⁴ and R⁵ are independently selected from the group consisting of methyl and ethyl.

3. A method according to claim 2, wherein R³ is ethylene.

4. A method according to claim 3, wherein R⁴ and R⁵ are ethyl.

5. A method according to claim 4, wherein the compound is administered 2-4 times per day in a dosage unit between about 15 and 50 mg. of the compound.
